Primary Examiner — Garth Rademaker*Assistant Examiner* — Katie Stofko Mroczka(74) *Attorney, Agent, or Firm* — Birch, Stewart, Kolasch & Birch, LLP(57) **CLAIM**

The ornamental design for a tablet computer, as shown and described.

DESCRIPTION

FIG. 1 is a bottom perspective view of a tablet computer showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view thereof showing the tablet computer in a disassembled state in which the display part is detached from the keyboard part and the stand portion of the display part is in an opened configuration;

FIG. 9 is an enlarged view of the left-bottommost part of FIG. 8; and,

FIG. 10 is a rear perspective view of FIG. 8.

The broken lines depict portions of the tablet computer that form no part of the claimed design.
